CONTAINER END

Richard J. Brincks, Wheeling, William L. Fox, Jr., Libertyville, and Henry S. Holc, Barrington, Ill., assignors to American Can Company, Greenwich, Conn.

Filed Aug. 10, 1972, Ser. No. 279,308

Term of patent 14 years

Int. Cl. D9—07

U.S. Cl. D9—255

FIG. 1

FIG. 3

FIG. 2

FIG. 3

FIG. 4

FIG. 5

FIG. 6

FIG. 1 is a top plan view of a container end showing our new design.

FIG. 2 is a cross-sectional view taken along line 2-2 of FIG. 1.

FIG. 3 is a top plan view of a modified form of our new design wherein the pour tab is oval and is hinged at the side.

We claim:

The ornamental design for a container end, substantially as shown and described.
